UNITED STATES PATENT OFFICE

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

THREAD-WAXING DEVICE.

Original application filed April 7, 1916, Serial No. 89,560. Divided and this application filed November 21, 1919. Serial No. 339,651.

To all whom it may concern:

Be it known that I, FREDERIC E. BERTRAND, a citizen of the United States, residing at Lynn, in the county of Essex and 5 State of Massachusetts, have invented certain new and useful Improvements in Thread-Waxing Devices; and I do hereby declare the following to be a full, clear, and exact description of the invention, such as 10 will enable others skilled in the art to which it appertains to make and use the same.

The present invention relates to thread waxing devices for sewing machines and has special reference to stripping devices for 15 stripping the wax from the thread as it is drawn from the thread waxing device by the thread handling devices of the sewing machine.

An object of the present invention is to 20 provide a novel and improved stripping device of this type which is simple in construction and efficient and economical in use.

With this object in view a feature of the present invention contemplates the provision 25 in a thread waxing device of a stripping device comprising two cooperating oppositely disposed stripping members having overlapping portions forming opposite walls of a passage for the thread which 30 passage is arranged transverse to the plane of said overlapping portions. Preferably, the stripping members are equilateral and have corner portions thereof overlapping to form the thread passage so that when one set

35 of corners become worn, other corners of the stripping members may be used. In the preferred embodiment of the invention the stripping members are triangular in shape, and means of simple construction is pro- 40 vided for removably securing the stripping members in place and for relatively adjusting the stripping members to regulate the size of the thread passage. As illustrated in the accompanying drawings, the stripping

45 device comprises two spirally formed strip- ping members, the coils of which are tri- angular in shape and arranged one above the other, and the adjacent corners of which are arranged in overlapping relation to form a 50 relatively long thread passage.

Other features of the present invention comprise certain constructions, arrangements, and combinations of parts herein-

after described and claimed, the advantages of which will be obvious to those skilled in 55 the art.

The several features of the present invention will be clearly understood from the following description and accompanying drawings in which:

Figure 1 is a side elevation of a thread waxing device embodying the features of the invention in their preferred form; Fig. 2 is a detailed plan view of the improved stripping device; Fig. 3 is a vertical section of the upper portion of the device illustrated in Fig. 1; and Fig. 4 is a detailed side elevation of one of the stripping members.

The thread waxing device as illustrated in 70 the drawings is particularly adapted for use in a shoe sewing machine such as the one illustrated and described in applicant's co-pending application Serial No. 89,560, filed April 7, 1916, of which the present application 75 constitutes a division. The device comprises a wax pot 10, the upper end of which is closed by a cover 12, and within the wax pot is mounted a thread truck 14 over which the thread passes. As the thread is being 80 drawn from the waxing device by the thread handling devices of the sewing machine, it passes through a stripping device which removes the superfluous wax from the thread. As illustrated in the drawings, the stripping 85 device comprises two spirally formed strip- ping members 16 of spring wire, the coils of each of which are triangular in shape and arranged one above the other. The strip- ping members, when in operative position, 90 are positioned so that their inner corners are arranged in overlapping relation to form a passage for the thread between them as shown in Figs. 2 and 4. The stripping members are mounted within a housing or 95 chamber 18, the bottom wall of which is pro- vided with an aperture 20 through which the thread passes to the stripping device. The stripping members rest upon the bottom 100 wall of the chamber 18 and their forward sides engage the forward wall 22 of the chamber which wall projects inwardly and is V-shaped to fit the forward sides of the stripping members. The stripping mem- bers are held in place against the wall 22 of 105 the chamber by means of a clamping block

24, the forward face of which is V-shaped to engage the rear sides of the stripping members. The clamping block 24 is adjustable toward and from the stripping members by means of a screw 26 threaded through an aperture in the rear wall of the chamber 18 and having its inner end engaging a socket in the clamping block. With this construction it will be seen that when one set of corners of the stripping members have become worn, the stripping members may be repositioned so that a fresh set of corners may be used, and when these in turn become worn, the remaining set of corners may be used. Also, by adjustment of the clamping block 24, the stripping members may be relatively adjusted to regulate the passage for the thread through the stripping device so as to leave any desired amount of wax on the thread.

25 The nature and scope of the present invention having been indicated, and a device embodying the several features of the invention in their preferred form having been specifically described, what is claimed is:

1. A thread waxing device of the class described having, in combination, polygonal-shaped stripping members having overlapping corner portions provided with internal surfaces cooperating to form a passage for the thread between them and capable of being rearranged to cause different corner portions to form the thread passage, and means for holding the stripping members in position.

2. A thread waxing device of the class described having, in combination, polygonal-shaped stripping members having overlapping portions provided with internal surfaces cooperating to form a passage for the thread between them and capable of being rearranged to cause different corner portions to form a thread passage, means for holding the stripping members in position, and means for relatively adjusting said stripping members to vary the size of the passage for the thread.

3. A thread waxing device of the class described having, in combination, polygonal-shaped stripping members of wire having overlapping corner portions cooperating to form a passage for the thread between them and capable of being rearranged to cause different corner portions to form the thread passage, and means for holding the stripping members in position.

4. A thread waxing device of the class described having, in combination, two co-operating oppositely disposed stripping members having overlapping portions provided with internal surfaces forming opposite walls of a passage for the thread positioned transverse to the plane of said overlapping portions.

5. A thread waxing device of the class

described having, in combination, triangular-shaped stripping members of wire having overlapping corner portions cooperating to form a passage for the thread between them.

6. A thread waxing device of the class described having, in combination, triangular-shaped stripping members of wire having overlapping corner portions cooperating to form a passage for the thread between them, and means for relatively adjusting said stripping members to vary the size of the passage for the thread.

7. A thread waxing device of the class described having, in combination, triangular-shaped stripping members of wire having overlapping corner portions cooperating to form a passage for the thread, and means for removably securing said members in place.

8. A thread waxing device of the class described having, in combination, triangular-shaped stripping members having overlapping corner portions to form a passage for the thread, and means for holding said stripping members in place comprising co-operating clamping members having V-shaped walls to engage the adjacent sides of said stripping members on opposite sides of the passage for the thread.

9. A thread waxing device of the class described having, in combination, triangular-shaped stripping members having overlapping corner portions to form a passage for the thread, and means for holding said stripping members in place comprising co-operating clamping members having V-shaped walls to engage the adjacent sides of said stripping members on opposite sides of the passage for the thread, said clamping members having provision for relative adjustment toward and from each other.

10. A thread waxing device of the class described having, in combination, two spirally formed stripping members having polygonal coils, the adjacent corners of which stripping members are arranged to form a passage for the thread.

11. A thread waxing device of the class described having, in combination, two spirally formed stripping members having triangular coils the adjacent corners of which are arranged to form a passage for the thread, and means for relatively adjusting said stripping members to vary the size of the passage for the thread.

12. A thread waxing device of the class described having, in combination, a chamber having an inwardly projecting V-shaped wall, two spirally formed stripping members, the coils of which are triangular in shape having adjacent corners arranged to form a passage for the thread, one side of each stripping member being adjacent a side of the V-shaped wall respectively, and

means for clamping the stripping members against said wall.

13. A thread waxing device of the class described having, in combination, a chamber having an inwardly projecting V-shaped wall, two spirally formed stripping members, the coils of which are triangular in shape having adjacent corners arranged to form a passage for the thread, one side 10 of each stripping member being adjacent a side of the V-shaped wall respectively, and a member adjustable toward and from

said wall for clamping said members against said wall.

14. A thread waxing device of the class described having, in combination, polygonal-shaped stripping members having corner portions constructed and arranged to cooperate to form a passage for the thread and capable of being rearranged to cause 20 different corner portions to form the thread passage, and means for holding the stripping members in position.

FREDERIC E. BERTRAND.
